DENTURE RETAINING MEANS

James Patrick Dillon, New York, N. Y.

Application February 7, 1948, Serial No. 6,838

1 Claim. (Cl. 32—5)

2

My present invention relates to dentures and more particularly to a novel support for a removable bridge or denture wherein simplified means is provided for retaining the denture in place.

Heretofore, various means have been utilized to support dentures in position. Many of these required securing elements which directly engaged live teeth on opposite sides of the gap to be bridged.

Such securing elements are often constructed to engage the live teeth at or near the gum and, therefore, at or near the area where the enamel is weakest. This frequently leads to abrasion of the enamel, exposure of the underlying section of the vital tooth and general discomfort.

Various attempts have been made to provide securing elements for the bridge or other removable denture wherein the securing elements were fixed by various means into or to the vital teeth on opposite sides of the gap.

Such elements have, however, been complex in construction necessitating a relatively large amount of work in the mouth of the patient and resulting in severe discomfort.

My invention is directed to a simplified denture support comprising essentially two cooperating elements on each side of the denture, one of the elements constituting a simple stud or button secured to a vital or permanent tooth coacting with the slotted element in the removable bridge of the denture.

These members may, of course, be reversed as to their relative positions, but the simplicity and compactness of the stud makes it preferable that the stud be the element which is permanently secured in the mouth.

Essentially, the stud which comprises a small shank and a node on the end of the shank is secured into or to the surface of the vital tooth which is directed toward the gap and thus provides the element on which the denture may be secured or suspended.

The stud may be secured to a crown which is fitted over the vital tooth or to a plate which is secured to the surface of the vital tooth, or the shank thereof may be embedded by any of various means well known in the art in a slot excised from the vital tooth.

Thus, the dentist to prepare the vital teeth on each side of the gap for the introduction of the removable denture need merely treat the surface of the vital tooth or otherwise prepare it for the positioning of the simple crown carrying the stud.

The denture may then be prepared with the appropriate slots engaging the studs on opposite sides. The slotted elements preferably are a force fit over the studs so that they will remain in position either in the lower or upper portion of the mouth as the case may be; but the denture may be so arranged that it need not press tightly on the gums immediately below, most of the load being taken by the studs on the vital teeth on opposite sides of the gap until the mouth becomes accustomed to the denture, whereupon the denture may then be readily adjusted so that the major portion of the load or all of it, as desired, is taken by the gum. This adjustment may be a progressive one as needed.

The vital teeth on opposite sides of the gap are, of course, supported and themselves reinforced by the denture between them so that any biting or masticating load is transferred at least in part from the vital teeth should the load occur on the vital teeth across the denture and distributed therethrough.

The primary object of my invention, therefore, is the provision of a novel removable denture structure.

Another object of my invention is the provision of novel means for supporting the denture in position.

Another object of my invention is the provision of a denture support arranged so that the vital teeth carry stud elements and the removable denture is provided with opposite slot elements registering with and matching the studs.

Another object of my invention is the provision of novel means for forming the studs.

Another object of my invention is the provision of novel adjustable slotted elements for co-operating with the studs.

Another object of my invention is the provision of novel means for predetermining the angular position of the denture with respect to the studs and hence with respect to the vital teeth and the remainder of the mouth.

Another object of my invention is the provision of simplified means for temporarily or even permanently securing the denture in place in the event that any of the denture supporting elements is broken.

Another object of my invention is the provision of denture support elements in which the elements located in the mouth and on the denture are readily replaceable individually and in which the single support member or members placed in the mouth may be utilized with various dentures as the occasion may require.

Another object of my invention is the provision of novel denture support members simplified in construction and so arranged as to promote cleanliness, avoid areas or sections in which undesirable deposits may form and which will give a natural appearance to the entire structure.

Another object of my invention is the provision of novel denture support means so arranged that the wearer of the denture may readily, if required, remove and replace the same as the occasion arises.

The foregoing and many other objects of my invention will become apparent in the following description and drawings in which:

Figure 1 is a partially expanded view in perspective showing the arrangement of my novel denture and its relation to the permanent teeth in the mouth.

Figure 2 is a view in perspective of one form which my novel slotted element may take.

Figure 3 is a view in perspective of one form which my novel stud element may take.

Figure 4 is a cross-sectional view showing my novel denture of Figure 1 in position between the vital teeth.

Figure 5 is a top plan view showing my novel denture in position.

Figure 6 is a cross-sectional view showing a slightly modified form of the novel denture construction of Figure 4.

Figures 7 and 8 are views in perspective partly broken away showing the interlocking of the two elements of my denture.

Figure 9 is a view in perspective of a wire utilized in place of the clasp member of my removable denture.

While my invention is primarily directed to a removable bridgework, the simplicity of construction and the permanence of the attachment is such that it may as readily be used in permanent bridgework as well.

Referring first to Figures 1, 2, and 3, I have here shown a removable denture 30 having the artificial teeth 31 and 32 and the gum simulating rest 33 arranged to be placed over the natural gum 34 in the mouth between the vital or permanent teeth 35, 36.

The surfaces of the teeth 35, 36 facing the gap 34 are provided with the studs 40 each comprising the shank 41 and the node or button 42.

In Figure 3 the button 42 and its shank 41 are shown mounted on a plate 43 which may be secured to the vital tooth or a crown or an inlay thereof, or which may be a part of a crown or inlay as hereinafter described.

The ends of the denture 30 which abut the faces of teeth 35 and 36 which face the gap 34 are provided with the dog or clasp members 45 of Figure 1 formed essentially of a U-shaped channel having a supporting leg 46 and a bifurcated leg 47 provided with the slot 48 defining in turn the subsidiary legs 49 and 50.

The supporting leg 46 of the dog or clasp member is provided with a horizontal extension 52 which in turn provides for interengagement and support of the dog or clasp element with the removable denture.

The bridge 30 comprising the teeth 31 and 32 is formed of any suitable material, such as acrylic material or the like, having a natural finish corresponding to the appearance of the remaining teeth in the mouth. The dog or clasp members 45 and their rearward extensions 52 are secured in the teeth 31, 32.

When the bridge is moved into the gap 34,

the legs 49 and 50 on opposite sides of the slot 48 are positioned over the shank 41 between the button and the surface of the tooth so that these legs are captured therebetween, and the button 42 is in turn captured between leg 47 of the dog or clasp 45 and its supporting leg 46.

Both the button 42 and the supporting clasp or dog 45 may be made of suitable material, such as stainless steel, and the legs 49 and 50 on opposite sides of the slot 48 may be made adjustable within a limited range to create appropriate tension for ensuring the accurate and permanent positioning of the removable bridge.

Thus, the legs 49 and 50 may be pinched together slightly or the main legs 41, 46 may be moved toward or away from each other to create and vary this tension.

Preferably, the rearward supporting extensions 52 are themselves arranged so that the clasps or dogs 45 may be moved in and out to obtain a final adjustment as the dentist is fitting the bridge to the mouth.

For this purpose, the supporting members 52 instead of being directly embedded in the bridge 30 are arranged so that they fit tightly in the sleeve 55 embedded in the bridge 30 and may be moved axially with respect to each other.

In order to secure this adjustment, the rearward extensions or rods 52 are preferably knurled; and also at the time of insertion thereof into the sleeve 55 a drop of solder may also be incorporated.

After the adjustment is made, the application of heat to the dog or clasp 45 at each end will by conduction into the sleeve 55 melt the solder and make this adjustment a permanent one.

The clasp or dog 45 is as shown in Figures 4, 5, and 6 mounted in a recess 57 of the removable denture so that when the removable denture is in position as shown in Figures 1, 2, 6, and especially Figure 5, all of the supporting structure is completely concealed, and the teeth, including the removable denture, present a smooth natural appearance on the distal, the proximal side, and the biting surface.

The presence of the denture can only be detected if the user actually removes the same from his mouth.

In Figure 3 I have shown a rod 52 extending from approximately the middle of the supporting leg of the dog or clasp 45 along approximately a center axial line of the denture 30. This supporting member may be arranged in various positions in different structures and as shown in Figure 6 the sleeve 55 and the supporting legs 52a may extend from the bottom of the supporting leg 46 of the clasp or dog 45.

In Figures 7 and 8 I have shown the manner in which the dog or clasp 45 engages the button 42. These figures, in combination with the elements shown in Figure 1, demonstrate the simplicity of my novel denture.

A minimum of work must be done in the mouth and the supporting or interlocking members are so simple that the amount of work done in preparing the denture itself is greatly reduced, thereby reducing the complexity and the expense of the bridgework.

The simplicity of the units, the smooth surfaces, and the absolute reduction of the number of elements, curves, angles, and recesses promotes cleanliness by providing fewer recesses in which food particles may be caught and retained.

The method of attaching the button to the vital or permanent tooth may follow any of the

standard procedures for attaching other elements to a tooth.

Thus, the button may be attached to or be made part of a crown or an inlay. It may be mounted on a plate and the plate inlaid or otherwise secured to the vital or permanent tooth.

In Figure 4 the vital or permanent teeth on either side of the gap have been shown as the prepared teeth 35a and 36a carrying a finished plastic crown 70, 71 reinforced by a pulverized core or shell 72, 73. The pulverized core or shell has been soldered at 75, 76 to the plate or flock 43 of the button 42.

In Figure 6 the button 42 is shown soldered directly to a cap 80 or 81 on the prepared teeth 35b, 36b.

In the constructions thus far shown the denture is so arranged that it may rock slightly with respect to the other teeth during use. This rocking action within reasonable limits simplifies the accurate adjustment of the bridge in the mouth and also provides a resilience to the bridge comparable to the slight resilience or flexibility of the permanent teeth in the mouth.

In Figure 9 I have shown a variation 145 of my clasp or dog for interengagement with my novel stud 42, the said variation comprising a wire having two parallel elements 146 and 147 bent into a parallel loop as shown and twisted or connected at 152 into a supporting element which may be inserted in or carried in the removable denture.

As shown in Figure 9 this wire may be readily utilized to receive in engagement button 42 with the shank 41 resting against the top section 150 which connects elements 147 and 145 of the wire.

The various clasp elements shown herein should as previously pointed out be slightly flexible and preferably even resilient so that minor adjustments thereof can be made. They should also be inert in the mouth so that they will not combine with the mouth acids to corrode or form corrosion products.

Thus, a preferable composition for the various clasp or dog members here shown as well as for the clasp member is a bendable alloy preferably consisting of 50% 24 K gold, 40% silver, and 10% copper.

This composition produces a denture structure which is rich yellow in color. To whiten the

composition, from 1% to 13% of exzilium may be fused thereto depending on the color desired. To strengthen the composition, from 1% to 13% of platinum may be added. The metal thus produced is castable, does not tarnish and fuses with other metals as needed.

In the foregoing, I have described my invention solely in connection with specific illustrative embodiments thereof. Since many modifications and variations of my invention will now be obvious to those skilled in the art, I prefer to be bound not by the specific disclosures herein contained but only by the appended claim.

I claim:

15 Denture retaining means for interengaging a removable denture element with a permanent dental element comprising a stud said stud having a shank member secured to one element at one end thereof and a button on the opposite end of the shank carried by the permanent element and a slotted clasp carried by the removable denture and releasably engageable with said shank and button of the stud; said slotted clasp comprising a wire bent to define a slot and additionally bent to define an extension engaged by said removable denture and additionally bent to form a semi-circle section to rest on the button of said stud.

30 JAMES PATRICK DILLON.
